BOTTLE WASHING APPARATUS

Albert S. Jackson, Wood River, and Clarence A. Heyne and John R. Johnson, Alton, Ill., assignors to Owens-Illinois Glass Company, a corporation of Ohio

Application December 7, 1939, Serial No. 308,044

18 Claims. (Cl. 15—64)

The present invention relates to improvements in bottle washing machines and more particularly to a washer of the immersion type adapted to automatically remove misprinted or smeared colored designs, labels, and similar decorations from the exterior surface of the bottle before they have been permanently baked thereon. Various types of paint or enamel coloring material are employed in this decorating operation.

An object of the invention is the provision of a continuously rotating machine adapted to receive bottles on which decoration or printing has been improperly applied or smeared due either to handling or defective operation of the decorating machine, and immerse them automatically first into a solvent solution and then a rinsing bath.

Another object is the provision of means submerged in the several baths for mechanically aiding in the removal of undesirable surface decoration.

A further object is the provision of novel ware-holding means for automatically grasping and releasing the bottles at the loading and unloading station and capable of handling a wide range of sizes of articles without adjustment.

Another object will become apparent during the course of the following description:

In the drawings:

Fig. 1 is a vertical sectional view through the bottle washer;

Fig. 2 is a vertical transverse sectional view through the cleaning brush holder taken on line 2—2 of Fig. 1;

Fig. 3 is a partial plan view of the apparatus with parts broken away;

Fig. 4 is a sectional elevational view of an intermediate ware squeegee showing a bottle passing thereover;

Fig. 5 is a similar view showing the bottle in cleansing position;

Fig. 6 illustrates a modified form of squeegee;

Fig. 7 is a vertical sectional view through a bottle holding chuck in closed position;

Fig. 8 is a similar view of the chuck in open or loading position;

Fig. 9 is a vertical sectional view illustrating the mechanism for rotating the chucks;

Fig. 10 is a sectional elevational view of the chuck supporting mechanism taken on line 10—10 on Fig. 8;

Fig. 11 is a plan view of the solvent and rinsing tanks; and

Fig. 12 is a sectional view through the tank taken on line 12—12 of Fig. 11.

The apparatus illustrated in the accompanying

drawings is particularly adapted for use where quantities of bottles of the type generally used for beverages are handled. The art of applying surface decoration to beverage bottles of all types is rapidly gaining favor over the use of gummed labels or the more expensive cutting of special molds for the manufacture of the ware. The decorating art has so far developed that surface decoration when once applied to the bottle and baked or otherwise fused thereon becomes practically indestructible. Several methods of applying color to glassware may be employed, the one most generally used being the silk screen process which employs ceramic pigments in a plastic or semi-fluid state. After the color is applied to the ware, it must pass through an oven at a comparatively high temperature to fuse the pigment to the glass. Until the decorated ware reaches the oven, the color remains more or less soft and 15 is readily smeared by accidental contact with other ware or by inadvertent handling. It occasionally happens that an inaccuracy will develop in the decorating machine, thus causing a misprint of the design or lettering being applied 20 which will remain unnoticed until several bottles have passed through the machine. The decorating machine operator usually cannot spare sufficient time from his duty to do more than remove the smeared ware from the production line. The 25 smeared or off-ware may then be collected and removed to a point where it may be properly cleaned and prepared for redecoration.

At times when much ware is being handled by a number of decorating machines, the amount of 30 off-ware rapidly increases. The time consumed in cleaning the smeared ware by hand soon becomes excessive and the elimination of much of the previous effort is accomplished by the machine forming the basis of this invention. The 35 apparatus briefly, includes a continuously rotating table having a plurality of bottle holding devices thereon into which the neck of the bottle to be cleaned is inserted. The bottles are lowered to submerge the smeared surface in a solvent solution and are rotated while so submerged, 40 against a series of brushes which, with the aid of squeegees, tend to remove the decoration softened by the solvent. The bottles are then transferred to a rinsing bath for final cleansing before removal from the machine. A detailed description 45 of the apparatus immediately follows.

Referring to Figs. 1, 3, 9, and 11 of the accompanying drawings, the machine embodying our invention includes a base 15 of channel and I-beam construction on which a vertical sta-

tionary column 16 is mounted. The column 16 rotatably supports a circular table 17 on which is mounted a plurality of ware-holding chucks 18. The table is rotated continuously in a clockwise direction by means of an adjustably mounted drive motor 19 and speed reduction gearing 20 which carries a drive pinion 21 meshing with an internally toothed ring gear 22 secured to the under side of the table 17.

The chucks 18 for holding the bottles are adapted to be independently moved vertically through an arc of approximately 60° (Figs. 3, 7, and 8). The chucks are elevated (Figs. 3 and 8) at the loading and unloading station and are lowered to immerse the smeared or decorated surface of the bottles in the solvent and rinsing solutions. Each chuck unit 18 (Figs. 7, 8, and 9) includes a supporting member 25 or frame bolted to the table 17 and provided with bearing blocks 26 rotatably supporting a shaft 27 or spindle to which the chuck heads 28 are connected. The outer end of the spindle support 25 is provided with ears 30 to which chuck operating levers 31 in the form of bell cranks are pivoted by means of a hinge pin 32. The chuck head 28 includes a cylindrical cup-shaped holding member 33 formed of a spring material and saw-slotted to form a plurality of gripping fingers 34. A shaft 35 or shank formed on and extending from the base of the cup and in axial alignment therewith, is connected to the drive spindle 27 by a universal coupling 36. A chuck sleeve 38 surrounds the cup and shaft and is slidable thereon for causing the normally expanded fingers 34 to contract and grasp the bottle finish or neck, as the sleeve is moved in the direction of the cup as will be described presently. A resilient bushing 39 disposed within a retaining ring 40 is held in place within the cup 33 by a bottle centering pin 41 threaded into the base of the cup. This bushing simply provides a cushion which engages the bottle finish and prevents chipping thereof such as might otherwise occur during placing of bottles in the chucks.

Mechanism for actuating the sleeve 38 which contracts the chuck fingers (Figs. 7, 8, and 10) includes a separable ring 43 having secured therein a rotatable bearing 44 slidably mounted on the sleeve 38. A coil spring 45 surrounds the sleeve between the bearing 44 and a shoulder formed by the cup-shaped portion of the sleeve. The spring provides a yielding connection between the sleeve 38 and slidable ring 43. A nut 46 threaded on the inner end of the sleeve provides for positively opening the chuck. Bosses 47 formed on opposite sides of the ring 43 are adapted for pivotal connection to the outwardly extending arms 31a of the operating levers 31.

It will be noted by referring to Figs. 7 and 8 particularly that the pivotal point 32 of the levers 31 and ears 30 is located outwardly from and below the pivot of the coupling 36 to which the chuck head 28 is connected. Thus, as the chuck is lowered below the horizontal plane of the coupling, the ring 43 is moved forward in relation to the shaft 35 which compresses the spring 45 and through the latter moves the sleeve 38 outwardly into position to contract the fingers 34. Upon elevation of the chuck above a horizontal plane, the bearing 44 engages the nut 46 (Fig. 8) to draw the sleeve inwardly and thereby allow the fingers to open for removal of a cleansed bottle and reception of a bottle which is to be cleansed.

The raising and lowering of the chuck is accomplished by means of a slide bar 48 movable radially of the machine between guides 49 (Figs. 1 and 3). The outer end of the bar is connected by a link 50 to the downwardly extending arms of the levers 31. The inner end of the bar 48 (Figs. 1, 3, and 9) is provided with a cam roller 52 running in a cam 53 formed on a stationary plate 54 which is keyed to the column 16. The cam is shaped to operate through the cam rollers and slide bars to raise the chucks to the elevated position at a combined loading and unloading station A (Figs. 1, 3, and 11) and lower them for immersion of the bottles in the several solutions. The container for the solutions is divided into several compartments as will be brought out presently, thereby necessitating raising the bottles sufficiently to clear the separating partitions.

Continuous rotation of the chuck is accomplished by means of a beveled pinion 55 pinned to the chuck spindle 27 and meshing with a ring gear 56 bolted to a supporting spider 57 (Fig. 9). The spider is rotatably mounted on the column 16 and is supported thereon on bearings 58 mounted on the stationary plate 54. A ring gear 60 bolted to the spider meshes with a gear 61 keyed on the upper end of a shaft 62 which is journaled in the plate 54. The shaft carries on its lower end, a second gear 63 meshing with an internal ring gear 64 bolted to the table 17. As the table 17 travels in a clockwise direction, gears 61 and 63 are rotated in a like manner, thus imparting motion in a counter-clockwise direction through the external gear 60 to the spider 57. It will be noted that rotary motion is thus transmitted to the chuck spindles in a clockwise direction for reasons which will become apparent presently.

Bottles to be cleansed are placed in the chucks at the loading station A (Fig. 11) and are lowered by the cam 53 into an arcuately shaped tank 65, or trough, which substantially surrounds the table 17 and is spaced a slight distance therefrom. The tank is divided into separate compartments as shown in Fig. 11, the first and preferably larger section 66 containing a suitable solvent solution. The center section 67 may be employed for either additional solvent or a primary rinsing, both depending upon the ability of the solvent to completely disintegrate the color pigment. The last section 68 contains a rinsing bath for removing the coating of solvent or any particles adhering to the surface of the ware.

Additional means for aiding in the removal of color from the bottles include a series of brushes 70 removably supported within the tanks and disposed at an angle to the bottom thereof. Each brush comprises a bristle holder 71 or plate having rows of bristles 72 secured thereto at a slight angle to the plate. In Fig. 3 the first group of brushes is shown with the bristles removed for the purpose of clearly disclosing the angular positioning of these brushes. The bristles are formed preferably from a non-corrosive or rust-resistant metal and have their ends bent at approximately a right angle 73 in the direction of the approaching ware as shown in Fig. 2. It will be seen that as a bottle passes the brush the turned ends of the bristles will exert a greater scraping action against the surface than would normally straight bristles. The brush holders are spaced sufficiently close together to create a substantially continuous brushing action as the bottles pass through the solvent, thereby removing the pig-

ment as it is dissolved. The level of the solvent is maintained at a height to adequately cover the brushes and a substantial portion of the ware passing therethrough. Rotation of the ware as it passes over the brushes augments the cleansing action of both the bristles and solvent.

As the bottles are passing over the brushes they are subjected to further wiping by periodical contact with squeegees 75 formed of a resilient material, such as for example, sponge rubber or the like. The squeegees are mounted in holders 76 which are secured to the rim of the tank 65 (Figs. 5 and 9). A modified form of squeegee illustrated in Fig. 6 includes a holder 78 arranged to support a pair of rubber squeegees 75' between which the bottle must pass. It may at times be found desirable to replace one or more brushes with a squeegee of this type.

The bottles when passing from one tank to the other, are raised momentarily to a substantially horizontal position as they pass over the partition and while in this position are wiped over a squeegee 79 extending upwardly from the partition to which it is secured. This wiping action drains excess fluid from the surface of the ware and tends to eliminate contamination of the liquid in succeeding tanks. During such positioning the chucks are contracted to firmly hold the bottles.

The action of both solvent and rinsing liquids may be increased by heating to a predetermined temperature and for this purpose we propose to employ electrical immersion heaters 89, one of which is indicated in Fig. 5. It will be understood that to maintain the desired temperature, several such heating units may be necessary for each section of the tank.

The tank sections 66, 67, and 68 are each provided with drain openings 82 for use when it becomes necessary to remove sediment or change the solutions. The rinsing tank 68 is provided with an overflow trough 83 to compensate for the constant addition of water through a supply pipe 84. The water is permitted to flow slowly from the pipe through a plurality of ports 85 or holes drilled therein, thus producing a circulation of clean water within the tank so that contamination of the rinsing bath may be reduced to a minimum.

Modifications may be resorted to within the spirit and scope of the appended claims.

We claim:

1. In an apparatus of the character described, a continuously rotating table, an annular series of bottle holders carried by said table each including a chuck, a stationary tank partially encircling the table and containing a cleaning fluid, means for actuating said holders to lower and raise bottles into and out of the tanks, and means forming a part of each holder for actuating the chuck to automatically grasp and release the bottles.

2. An apparatus of the character described, comprising a table, means for continuously rotating the table about a vertical axis, a plurality of ware holding chucks carried by said table, a stationary sectional tank partially encircling the table for holding a cleaning fluid, means for actuating said chucks to lower and raise ware held therein into and out of the tank, and means for automatically opening and closing said chucks at a combined loading and unloading station.

3. An apparatus of the character described, comprising a table mounted for rotation about a vertical stationary central column, means for imparting continuous rotary motion to the table, a plurality of rotatable ware holding chucks se-

cured to the table, the axis of said chucks being disposed in a substantially horizontal plane, a stationary sectional tank partially encircling the table for holding a cleaning fluid, means for actuating said chucks to lower and raise ware held therein into and out of the tank, means for automatically opening and closing said chucks at a combined loading and unloading station, and means for continuously rotating the chucks about their individual axes.

4. An apparatus of the character described, comprising a table mounted for rotation about a vertical stationary column, means for continuously rotating said table, a series of rotary bottle holding chucks carried by the table, a segmental stationary trough partially encircling the table and adapted to contain cleaning liquids, means for raising and lowering said chucks at predetermined intervals to immerse ware carried thereby in the liquids in succession, means for continuously rotating the chucks about their individual axes, and means for automatically opening and closing said chucks at a combined loading and unloading station.

5. A bottle washing apparatus of the character described, comprising a rotatable table, means for continuously rotating the table, radially disposed rotary bottle holding chucks carried by the table, means for continuously rotating said chucks in a substantially horizontal plane about their individual axes, a sectional stationary trough partially encircling the table and adapted to contain solvent and rinsing solutions respectively, means for lowering said chucks to immerse ware carried thereby into said solutions in succession, mechanical means disposed within the trough for accelerating cleansing of the bottles, and means for automatically opening and closing said chucks at a combined loading and unloading station.

6. A bottle washing apparatus of the character described, comprising a rotatable table, means for continuously rotating said table, radially disposed rotary bottle holding chucks carried by the table, means for continuously rotating said chucks in a substantially horizontal plane about their individual axes, a sectional stationary trough partially encircling the table and adapted to contain solvent and rinsing solutions respectively, means for lowering said chucks to immerse ware carried thereby into said solutions in succession, brushes disposed within the trough adapted to contact the moving surface of the ware for mechanically accelerating cleaning of the bottles, means engaging the ware at regular intervals for removing particles loosened by the solvent and brushes, and means for automatically opening and closing said chucks at a combined loading and unloading station.

7. A bottle washing apparatus of the character described, comprising a table mounted for rotation about a vertical axis, means for imparting continuous rotary motion to said table, a plurality of rotary bottle holding chucks carried by the table and projecting radially outward therefrom, means for causing continuous rotation of the chucks about their individual axes during movement of the table, a stationary arcuate tank adapted to contain a solvent solution disposed adjacent one side of the table, a rinsing tank disposed on the opposite side of said table, means for swinging said chucks and the bottles held therein vertically to immerse the ware in said tanks in succession, and means for opening and closing said chucks to receive and discharge the bottles.

8. A bottle washing apparatus of the character described, comprising a table mounted for rotation about a vertical axis, means for imparting continuous rotary motion to said table, a plurality of rotary bottle holding chucks carried by the table and projecting radially outward therefrom, means for causing continuous rotation of the chucks about their individual axes during movement of the table, a stationary arcuate tank adapted to contain a solvent solution disposed adjacent one side of the table, a rinsing tank disposed on the opposite side of said table, means for swinging said chucks and the bottles held therein vertically to immerse the ware in said tanks in succession, means disposed within each tank adapted to contact the bottles when lowered therein to mechanically aid the detergent action of the solutions, and means for opening and closing said chucks to receive and discharge the bottles.

9. An apparatus for removing mis-applied and unfired surface decoration from glass articles comprising a table mounted for rotation about a vertical axis, means for continuously rotating said table, a stationary arcuate tank adapted to contain a pigment dissolving solution disposed adjacent one side of the table, a rinsing tank disposed on the opposite side of said table, rotary article holding chucks carried by the table and projecting radially outward therefrom above said tanks, means for continuously rotating the chucks about their individual axes, means for swinging said chucks vertically to immerse the articles and transfer them from one tank to the other in succession, and means for automatically opening and closing the chucks at a combined loading and unloading station.

10. An apparatus for removing mis-applied and unfired surface decoration from glass articles comprising a table mounted for rotation about a vertical axis, means for continuously rotating said table, a stationary arcuate tank adapted to contain a pigment dissolving solution disposed adjacent one side of the table, a rinsing tank disposed on the opposite side of said table, rotary article holding chucks carried by the table and projecting radially outward therefrom above said tanks, means for continuously rotating the chucks about their individual axes, a plurality of brushes having upstanding bristles disposed within the tanks below the surface level of the solution, said bristles having their tips bent at substantially right angles in the direction of the approaching articles, means for swinging said chucks in a vertical plane to immerse the articles and bring them into contact with the bent tips of the bristles whereby to accelerate cleaning of the bottles, said swinging means being further adapted to elevate the articles for transfer from one tank to the other, and means for automatically causing the chucks to grasp and release the articles at a station between the ends of said tanks.

11. An apparatus for removing mis-applied and unfired surface decoration from glass articles comprising a table mounted for rotation about a vertical axis, means for continuously rotating said table, a stationary arcuate tank adapted to contain a pigment dissolving solution disposed adjacent one side of the table, a rinsing tank disposed on the opposite side of said table, rotary article holding chucks carried by the table and projecting radially outward therefrom above said tanks, means for continuously rotating the chucks about their individual axes, a plurality of brushes having upstanding bristles disposed within the tanks below the surface level of the solu-

tion, said bristles having their tips bent at substantially right angles in the direction of the approaching articles, means for swinging said chucks in a vertical plane to immerse the articles and bring them into contact with the bent tips of the bristles whereby to accelerate cleaning of the bottles, said swinging means being further adapted to elevate the articles for transfer from one tank to the other, means cooperating with said brushes for wiping loosened partially dissolved particles from the surface of the articles, and means for automatically causing the chucks to grasp and release the articles at a station between the ends of said tanks.

12. In a bottle washing apparatus of the character described, a table mounted for rotation about a vertical axis, stationary arcuately shaped solvent and rinsing solution containing tanks partially encircling the table, bottle holding chucks carried by said table and projecting radially and outward therefrom, means for automatically swinging said chucks vertically to alternately immerse and remove bottles into and from the solutions, each said chuck including an expansible cylindrical bottle holding head, and a sleeve slidably mounted on the head and movable in response to said swinging motion to alternately contract the head into holding engagement with a bottle placed therein and release said head to thereby automatically release the bottles at a discharging station.

13. In a bottle washing apparatus of the character described, a table mounted for rotation about a vertical axis, stationary arcuately shaped solvent and rinsing solution containing tanks partially encircling the table, bottle holding chucks carried by said table and projecting radially and outward therefrom, means for automatically swinging said chucks vertically to alternately immerse and remove bottles into and from the solutions, each said chuck including a cylindrical cup-shaped head, the wall of which is slotted to form a plurality of resilient bottle engaging fingers, a sleeve slidably mounted on the head and movable in response to said swinging motion to engage and alternately contract the fingers into holding engagement with a bottle placed therein at a loading station and release said head to thereby automatically release the bottles at a discharging station, and means for imparting continuous rotary motion to the chucks about their individual axes.

14. In a bottle washing apparatus of the character described, a trough adapted to contain a cleaning fluid, a table, a series of bottle holding chucks on the table movable in a path above said trough, means for imparting continuous rotary motion to the chucks about their individual axes, each said chuck including a horizontal driving shaft journaled in a supporting frame bolted to the table, a cylindrical cup-shaped head having a shank formed thereon universally coupled to said shaft, the side wall of said head being slotted to form a plurality of resilient bottle engaging fingers, a sleeve slidably mounted on the head and shank adapted at times to operatively engage and compress said fingers about a bottle neck, a ring slidably mounted for limited axial movement on that portion of the sleeve overlying the shank, a chuck operating lever pivoted for vertical swinging movement at its inner end on the supporting frame and at a point outwardly from and beneath the coupling of said shank and shaft, whereby upward movement of said lever above the horizontal plane of said shaft causes the

sleeve to be drawn inwardly to bottle releasing position and conversely the lowering of said lever operates to close said fingers, and means for automatically moving said lever at predetermined times.

15. Apparatus of the character described comprising an arcuate trough, transverse partitions dividing the trough into compartments, each compartment containing a cleaning fluid, an annular series of bottle holders movable in a path concentric with and above said trough, means for moving the holders continuously, means for moving the holders vertically at regular intervals to thereby lower bottles supported thereon into the compartments in succession and means for actuating the holders at a combined loading and unloading station to release cleansed bottles and position the holders to receive bottles which are to be cleansed.

16. Apparatus of the character described comprising an arcuate trough, transverse partitions dividing the trough into compartments, each compartment containing a cleaning fluid, an annular series of bottle holders movable in a path concentric with and above said trough, means for moving the holders continuously, means for oscillating the holders vertically at regular intervals to thereby lower bottles supported thereon into the compartments in succession and means for actuating the holders at a combined loading and unloading station to release cleansed bottles and position the holders to receive bottles which are to be cleansed.

17. In apparatus of the character described, a trough adapted to contain a cleaning fluid, a series of bottle holders movable in a path above

the trough, each holder including a normally expanded chuck adapted to be contracted about the neck of a bottle, a carrier for each chuck extending radially inward therefrom and including 5 means for imparting continuous rotation to the chuck about its longitudinal axis, a bell crank lever for imparting vertical movement to the chuck and a portion of the holder, means for rocking said lever, and means operable in response to said vertical movement of the lever for 10 effecting alternate expansion and contraction of the chuck.

18. In apparatus of the character described, a trough adapted to contain a cleaning fluid, a series of bottle holders movable in a path above 15 the trough, each holder including a normally expanded chuck adapted to be contracted about the neck of a bottle, a carrier for each chuck extending radially inward therefrom and including means for imparting continuous rotation to the chuck about its longitudinal axis, a bell crank lever for imparting vertical movement to the chuck and a portion of the holder, means for 20 rocking said lever, and means operable in response to said vertical movement of the lever for effecting alternate expansion and contraction of the chuck, said last named means including a sleeve movable to a position for contracting the chuck and devices connected to and movable by 25 said bell crank lever during the aforementioned vertical movement of the holder for actuating 30 said sleeve.

ALBERT S. JACKSON.
CLARENCE A. HEYNE.
JOHN R. JOHNSON.
